UNITED STATES PATENT OFFICE.

JAMES W. DOUGHERTY, OF MCKEESPORT, PENNSYLVANIA.

KIDDIE BRONCO.

Application filed December 5, 1922. Serial No. 605,087.

To all whom it may concern:

Be it known that I, JAMES W. DOUGHERTY, a citizen of the United States, residing at McKeesport, in the county of Allegheny and State of Pennsylvania, have invented a new and useful toy for children which I have named a Kiddie Bronco.

The following is a specification of my invention.

10 The object of my invention is to provide toy which will be attractive to children and provide them with an up and down motion similar to riding on a spring board.

I attain these objects by means of the device illustrated in the accompanying drawings, in which—

Fig. 1 is a side view of my toy, Fig. 2 is an end view. Throughout the views similar numerals will refer to similar parts.

20 In the figures the cross members 13 secured by bolts 14 to the rail 12 together with the side plates 10 secured to the rail 12 by means of bolts 15 constitute a supporting member which will hereinafter be called the support. Mounted between the plates 10 and fulcrumed therein by bolt 11 is the spring board 3, upon which is mounted the animal head 1 with the handle 2 secured therein, the screws 4 securing the head to

20 the spring board 3. In proximity to the head or handle 1 or 2 is the seat 5 and the back board 6 which together make a seat and back support when properly secured to the end of spring board. The numeral 7, a rubber buffer attached to the end of spring board to absorb the shock of impact in case the spring board 3 and the rail 12 come together. The numeral 8 refers to stirrups which are secured to the spring board 3

40 in proximity to the seat for the children to put their feet in when using this toy. The eye bolts 16 which are secured in the spring board 3 and the rail 12 are connected by the chain 18 which limits the movement of the spring board upward; this chain is arranged so its length may be adjusted to vary the movement of the spring board. The curved section 9 of the spring board 3 is a safety measure so the children cannot get their

50 fingers sheared off between 9 and the plates 10. The numerals 16 refer to eye bolts secured in the spring board 3 and the rail 12; these eye bolts are arranged at suitable points near the ends of rail and spring board so that the spiral spring 17 may be changed to different points to suit the load

on the seat 5. The spiral spring 17 furnishes the elastic springing action which makes this toy very desirable, it will be evident that many other kinds of springs could be substituted for the spring shown and obtain the same result; also it will be evident that there are many methods of supporting the spring board different to the method shown by which the same results could be obtained and I propose to anticipate every possible modification of this by which the same results can be obtained in the claims which will follow later.

To use this toy the child gets on the seat, 70 its weight causes the spring board to come down until the child's feet touch the floor; the child then pushes with its feet against the floor, this push of the feet coupled with the pull of the spring sends child off the 75 floor until the movement is restrained or the energy is absorbed, then the child descends and repeats the action. I also desire to mention that I sometimes use a spring in connection with the chain 18 for limiting 80 the movement of the spring board, this spring has a tendency to reduce the shock when the spring board comes to a stand still in its upward movement.

I claim as my invention the following: 85

1. A toy of the kind described, comprising a support, a spring board fulcrumed on said support, a seat with a back support mounted on the end of spring board, hand gripping handles mounted on said spring board in proximity to said seat, stirrups attached to said spring board in proximity to said seat, a spring attached to the end of spring board opposite to the end the seat is on, said spring having its 95 other end attached to the end of the support, means for varying the point of attachment of said spring on the spring board and the support, a chain attached to the spring board and the support for limiting 100 the spring board movement, a rubber buffer attached to the under side of said seat for reducing the shock resulting from impact between the seat and support, all substantially as described.

2. A toy of the kind described, comprising a support consisting of two cross members which rest upon the floor to form feet, a rail connecting the cross members upon which is securely mounted side plates which are provided with a hole and a pin for fulcruming thereon a spring board, a seat on

one end of spring board, handles mounted on spring board in proximity to said seat, stirrups attached to spring board in proximity to said seat, a rubber buffer attached 5 to the under side of seat, a spring attached to the end of spring board opposite to the end the seat is on, said spring having its other end attached to the cross rail on said support, means for varying the point of attachment of said spring on the spring board and on the cross rail, a chain attached to the spring board and the cross rail for limiting the movement of the spring board, all for 10 the purpose set forth and substantially as 15 described.

3. A toy of the kind described, comprising a support consisting of two cross members which rest upon the floor and act as feet, a cross rail secured to said cross members 20 near their middle, a pair of side plates secured to said cross rail, a spring board fulcrumed between said side plates, a seat on one end of said spring board, a figure head secured to said spring board in proximity 25 to the seat, a handle secured in said figure head, a spring attached to the end of spring board opposite to the end the seat is on, said spring having its other end attached to the

cross rail, and means for varying the point of attachment of the spring to the spring 30 board and the cross rail.

4. A toy of the kind described, comprising a support consisting of two cross members which rest upon the floor and act as feet, a cross rail secured to cross members near 35 their middle, a pair of side plates secured to said cross rail, a spring board fulcrumed between the side plates, said spring board being provided with a semi-circular section which is radial with the point of fulcrum, 40 a seat on one end of the spring board, a figure head on the spring board in proximity to the seat, a handle in the figure head, a spring attached to the end spring board opposite the end the seat is on, said spring having its other end attached to the cross rail, means for varying the point of attachment of the spring to the spring board and the cross rail, a chain attached to the 45 spring board and the cross rail for limiting 50 the movement of spring board, all for the purpose set forth and substantially as described.

I testimony that I claim the foregoing as my own I have hereto affixed my signature.

JAMES W. DOUGHERTY.
